UNITED STATES PATENT OFFICE.

JOHN E. BELL, OF BARBERTON, OHIO, ASSIGNOR TO THE BABCOCK & WILCOX COMPANY, OF NEW YORK, N. Y., A CORPORATION OF NEW JERSEY.

TRAVELING-GRAVE STOKER.

No. 857,011.

Specification of Letters Patent.

Patented June 18, 1907.

Application filed November 21, 1904. Serial No. 233,600.

To all whom it may concern:

Be it known that I, JOHN E. BELL, of Barberton, Summit county, Ohio, have invented a new and useful Traveling-Grate Stoker, of which the following is a full, clear, and exact description, reference being had to the accompanying drawings, forming part of this specification, in which—

Figure 1 is a side elevation of my improved stoker with parts of the furnace removed; Fig. 2 is a cross-section on the line II—II of Fig. 1; Figs. 3 and 4 are detail views showing the connection between the chain and grate-bar; Fig. 5 is a detail view of one of the scrapers; and Fig. 6 shows a modified form of slack adjuster.

My invention relates to the class of traveling chain grates, and it is designed to provide an improved construction which will hold the grate-bars in the desired position and prevent their sagging, also to provide for easy removal and repairs, and to avoid friction and binding.

In the drawings, I show grate-bars 2 having end lips or ears 3, which are removably bolted to outwardly projecting lugs 4 on the inner links 5 of traveling roller bearing chains having plain outer links 5'. The inner links 5 are of the form shown in Figs. 3 and 4, their end edges being inwardly inclined and the links overlapping at their lower ends. These links are connected at their overlapping lower ends by pins 6 carrying the rollers 7 and extending through the outer links 5'. The chain is provided with a roller 7 for each pin, these rollers resting upon upper and lower longitudinal tracks 8, 8' which I have shown as of angle-bar form and secured to the side-frame 9. U-shaped frames or tracks 10 extend from the inner ends of the upper tracks to the lower tracks which are lowered sufficiently to allow the rollers 7 to rest upon and travel over them. The front ends of the chains extend over sprocket-wheels 11 mounted upon a shaft 12 carried in fixed bearings 13 mounted in the external fixed portion of the side frame the teeth of said wheel being shaped to receive the chain rollers.

The supporting side-frames 9 of the grate may be either made separate from or secured directly to the grate-front 14 external to the furnace. I have shown them as separate from the front and being slotted (as shown at

14' in dotted lines in Fig. 1) and supported by the bearings on the main driving shaft. The side frames can then be adjusted with reference to the fixed driving shaft 13 by the threaded bolts 15, and slack in the chain thus taken up. In this construction, I have shown a bar or link 15^a connected to the side frame by a pin 15^b extending through a slot 15^c in the fixed cheek 14 within which the front end of the frames 9 extend. This bar or link 15^a has a lug 15^d which forms a nut for the screw 15, and the latter has a thrust bearing at 15^e against the fixed bracket 15^f. This arrangement is duplicated for each of the side frames 9.

Instead of forcing back the movable side frames with reference to the main shaft, by the threaded bolts at the front, I may take up the slack by making the rear curved frames 10 adjustable. Thus in Fig. 6 I show the frames 10 as movable upon guides extending from the side frames, and adjustable by the screws 15'. These screws may be operated by a rod extending from the front of the stoker. On account of the continuous support of the chains, however, they need not be pulled taut, since the supporting rollers prevent their sagging. The means for removing slack may therefore be dispensed with.

The depth of the coal fed in is regulated by an adjustable gate 16 having a firebrick lining, this being adjusted vertically by the screw 17 as shown.

The chains may be driven by any suitable connections.

I have shown the side frames which are connected by the transverse angle braces 18 as supported near their rear ends on rollers 19. These rollers enable the movable side frames to be adjusted by the front threaded bolts. I may also mount the front portion of the stoker on rollers 20 as shown in Fig. 1, so that these in combination with the rollers 19 will allow the entire machine to be moved out or from under the boiler on a track.

The chain and runway are preferably covered by cast overhanging plates 21 in the side walls of the furnace. I thus prevent dirt, ash or coal from sifting through the links and accumulating on the runway. I also preferably provide a scraper for clearing the tracks or runway, this being shown at 22 in Fig. 5. This scraper consists of an angled

blade which replaces one of the wheels or rollers of the chain and scrapes off or deflects the dust or dirt accumulating on the runway.

The advantages of my invention result from supporting the grate-bars at both ends throughout their travel. There is no danger of sagging of the chain, and the friction is reduced to a minimum. The grate may be operated with the chains slack, and hence the driving power may be reduced. The opening of the links due to sagging is prevented and the friction reduced. Any form of grate-bar may be used with as little or as much air space as desired. The grate-bars may also be easily removed and repaired. A further advantage results from the manner in which the chains are constructed. Both the inner and outer links of each chain are of such form that they can be easily stamped and shaped from plate steel. Heretofore, the links have been of such shape as to necessitate their being cast or forged. Cast links lack the necessary strength, and forged links are too expensive. By the simple provision of bending over the upper portions of the inner links, a secure seat is formed for the ends of the grate bars, no fitting of the parts being required. The inner and outer links being separately formed, any defective member can be readily removed and replaced. The flat, higher, inner links also largely protect the rest of the chain, and the rollers and run-way, from heat.

Sprocket wheels may be employed at the back end of the grate instead of the curved runways; and many other variations may be made in the form and arrangement of the chain, the grate-bars, &c., without departing from my invention.

40 I claim:

1. In a traveling grate, a pair of chains consisting each of inner and outer links, rollers journaled between the links of each chain, and grate-bars secured to the inner

links of the chain; substantially as described. 45

2. In a traveling grate, a pair of chains, consisting each of inner and outer links, pins connecting the inner and outer links of each chain, rollers journaled on the pins between the links, and grate bars secured to the inner links; substantially as described. 50

3. In a traveling grate, a pair of chains, consisting each of inner and outer links, the inner links having overhanging portions; rollers journaled between the inner and outer links of each chain, and grate bars removably secured to the inner links of each chain; substantially as described. 55

4. In a traveling grate, a pair of chains composed each of separable inner and outer links, the inner links having their upper end portions bent horizontally toward the outer link to form supports for the ends of the grate bars; substantially as described. 60

5. In a traveling grate, a pair of chains composed each of separable inner and outer links, rollers journaled between the links, and continuous run-ways for the rollers, the inner links of each chain having horizontal portions which extend toward the outer links which form seats for the grate bars; substantially as described. 70

6. In a traveling grate, a pair of chains, a series of transverse grate bars secured to and connecting the chains, rollers carried by each chain, and continuous run-ways for the rollers having curved end portions at least one of which is separate from, and adjustable with respect to, the other portions of the runway; substantially as described. 75 80

In testimony whereof, I have hereunto set my hand.

JOHN E. BELL.
